SNAP-ACTING DEVICE

Lyndon W. Burch, Bronxville, N. Y., assignor to
The Wilcolator Company, a corporation of Delaware

Application June 23, 1938, Serial No. 215,333

3 Claims. (CL 74—97)

This invention relates to actuators for switches, valves, and the like, and has particular reference to a novel actuator of the snap-acting type which is of a simple and durable construction and is positive and reliable in operation. The new actuator may be used to particular advantage in thermostats and accordingly will be specifically described in connection with such a device, although it is to be understood that its use is not limited to thermostats.

Snap-acting thermostats of various types have been devised heretofore, all of which include a member movable abruptly from one position to another at a critical temperature. One form of these thermostats comprises a dish-shaped bimetallic disc made up of two sheets of metal having different thermal coefficients of expansion and superimposed one on the other. Due to the unequal expansions of the two sheets upon a rise in temperature, internal stresses are developed in the disc which tend to change it to a shape of opposite curvature. However, the configuration of the disc is such that a change of shape is normally resisted until the internal stresses developed by the expansion attain a critical magnitude, whereupon the disc changes abruptly to a shape of opposite curvature. Thermostats of this form are objectionable for the reason that their operation is dependent on the use of bimetallic members, which are expensive. Also, since the bimetallic disc is operated by internal forces, it does not lend itself to "cold checking", that is, to calibration at room temperature to determine in advance the critical temperature at which it operates.

Another form of snap-acting thermostat devised heretofore derives its snap-action from a generally trough-shaped element made of sheet metal and adapted to buckle abruptly when stressed. In these devices, the stress may be imposed by an external source, such as a bimetallic element or a thermo-responsive bellows, or it may be imposed internally by making the trough-shaped element of bimetal. In either case, the stress is built up gradually without substantially changing the shape of the element, until the stress overcomes the bending resistance of the element due to its trough-shape, whereupon the element buckles along a line transverse to the direction of the trough, so that it becomes substantially straight transversely at the region of buckling. When the stress is released sufficiently, the element returns to its initial form with a snap-action. These devices, as previously made, have not been entirely satisfactory, because when

5 the trough-shaped element is made of bimetal it has the same disadvantages as the bimetallic disc, and when the element is made of a single metal it requires the use of a bellows or other thermo-responsive means acting on the element to buckle it.

10 The present invention, therefore, is directed to the provision of a novel snap-acting device of a simple construction which may be made thermo-responsive without the use of a bellows, a bimetallic element, or the like. In addition, the new device is adapted for manufacture at low cost, and readily lends itself to "cold checking."

15 A device made in accordance with the present invention comprises a flexible sheet bent into a trough-shape and disposed between confining means adapted to engage the sheet at each end near its longitudinal axis. The sheet is compressible endwise between the confining means, but by reason of the transverse curvature of the trough, the sheet may be compressed up to a critical amount without substantially changing its shape. However, when the compression exceeds the critical amount, the resistance of the sheet to bending is overcome, so that the sheet buckles abruptly and becomes substantially straight transversely at the center and slightly convex along the longitudinal axis, whereby the center of the sheet is moved abruptly in a direction normal to its surface. When the device is used in a thermostat, the endwise compression of the sheet may be obtained by making it of thermo-expansible metal so that a rise in temperature causes it to expand against the confining means, or the confining means may be thermo-responsive so that a change in temperature causes it to compress the opposite ends of the sheet, or, if desired, both of these expedients may be employed. In any case, the flexible sheet is subjected to endwise compression between the confining means and when the compression reaches a critical amount, the sheet buckles abruptly and, at the region of buckling, undergoes a rapid movement which may be used to actuate a switch, a valve, or the like.

20 In the preferred form of the new device, the trough-shaped element is retained at its ends in suitable seats mounted in a frame or casing and, when the device is used in a thermostat, is expandable by heat against the seats to subject it to compression. The seat at one end is adjustable toward or away from the opposite seat by suitable means, such as a handle, and by operating the handle the initial compression in the sheet 25 may be adjusted. The switch or other device to

be actuated may be disposed intermediate the ends of the sheet, so that the throw of the sheet incident to its buckling is transmitted to the device. Preferably, the amplitude of the motion transmitted from the sheet to the device to be actuated is adjustable by means operable to move the sheet and the device relatively toward or away from each other.

It will be apparent that in the new actuator the flexible sheet, by reason of its spring action and trough shape, constitutes a quick-acting element which is movable abruptly at its intermediate portion by endwise compression thereof. Accordingly, the sheet may be unimetallic, instead of bimetallic, its buckling action being independent of the unequal expansions of different metals. Since the buckling of the sheet is effected by endwise compression thereof, the snap action may be obtained by employing a simple thermo-expansible sheet, whereby the use of a bellows or other independent thermo-responsive means may be avoided. Also, since the sheet may be operated entirely by compression, the device may be readily "cold checked" by determining the coefficients of expansion of the sheet and its confining means, measuring the amount of compression necessary to buckle the sheet at room temperature, and calculating from these factors the increase in temperature required to produce the necessary critical compression.

For a better understanding of the invention reference may be had to the accompanying drawings in which—

Fig. 1 is a longitudinal section through one form of the new actuator;

Fig. 2 is a rear view of the device shown in Fig. 1;

Fig. 3 is a view similar to Fig. 2, with the snap-acting element removed;

Figs. 4, 5 and 6 are sections on the lines 4—4, 5—5 and 6—6, respectively, in Fig. 1;

Fig. 7 is an enlarged longitudinal section through the snap-acting element of the device shown in Fig. 1;

Fig. 8 is a perspective view of a modified form of the snap-acting element;

Figs. 9 and 10 are front and rear views, respectively, of another form of the new actuator;

Figs. 11 and 12 are sections on the lines 11—11 and 12—12, respectively, in Fig. 9;

Fig. 13 is a front view of the snap-acting element shown in Fig. 9, with the element in its normal position;

Figs. 14 and 15 are sections on the lines 14—14 and 15—15, respectively, in Fig. 13;

Fig. 16 is a view similar to Fig. 13, showing the snap-acting element in its buckled position, and

Figs. 17 and 18 are sections on the lines 17—17 and 18—18, respectively, in Fig. 16.

In the drawings, I have shown two forms of my new actuator used in connection with a switch, although it will be understood that the actuator is not limited to this use but may be used to operate a valve or other member.

Referring to Figs. 1 to 7, inclusive, the device there shown comprises a casing 20 made of a strong material having a low coefficient of expansion and which will not be weakened when subjected to high temperatures. I have found that a material suitable for the casing is a compound of alumina, silica and magnesium, such as Alsimag. The casing is formed in back with a longitudinal recess 21 and near one end has a passage 21' extending to the front of the casing

from the recess. At its front end, the passage 21' is enlarged to receive a plate 22 seated in the passage and secured to the casing by screws 23 (Fig. 5). The plate 22 is slotted, as shown at 5 22', and a double shouldered screw 24 is fitted in the slot with the shoulders of the screw engaging the opposite sides of plate 22, whereby the screw is held against axial movement relative to the plate. The screw 24 is threaded through one end of a mounting element 25 movable longitudinally in the passage 21', the mounting element being formed at its rear end with a V-shaped portion 26, the apex of which is seated against the casing at one end of the recess 21. By turning the screw 24, the mounting element 15 25 may be moved transversely of the casing in the recess.

The opposite end of the casing is formed with a longitudinal slot 28 in which a bell crank lever 29 is pivoted on a transverse pin 30. The pin and lever are inserted in the casing from the front with the pin disposed in a recess 30' in the front of the casing (Fig. 6), and the pin is held against the end wall of the recess by a plate 31, 20 one end of which is bent inwardly and extends into the recess 30' into contact with the pin. The plate 31 is seated against the front wall of the casing and is held in position by a bushing 32 loosely fitted in a passage 32' in the casing and 25 extending through the plate, the bushing having a head 33 seated against a suitable shoulder in the passage. A nut 33' is threaded on the front end of the bushing and screwed tightly against the plate 31.

30 Within the bushing 32 is a shaft 34 provided with threads 34' mating with internal threads in the bushing. At its front end, the shaft 34 carries an adjustment handle 35 which may be provided with a pointer (not shown) cooperating 35 with a suitable scale of temperature graduations. The inner end of shaft 34 extends through the head of the bushing and bears against a horizontal face 36 of the bell crank lever constituting one arm of the lever. The other arm of the lever is disposed in recess 21 and formed with a V-shaped notch 37.

Extending between the bell crank lever 29 and mounting element 25 is a generally trough-shaped member 40 made of sheet metal or the like, such 50 as a nickel-steel alloy, the member 40 being substantially straight in the direction of its longitudinal axis but curved in a transverse direction so that it forms a cylindrical segment (Fig. 4). The member 40 is doubled over at its ends, as 55 shown at 40', and has a clip 41 folded around one end and a clip 42 folded around the opposite end, the clips being pressed tightly against the ends of the member. The clips 41 and 42 are bowed slightly (Figs. 5 and 6) and are made 60 of a suitable material, such as Inconel, which will withstand high temperatures and maintain its shape indefinitely. I find that the member 40 may be made by forming the clips 41 and 42 into an arc shape and forcing them over the ends of 65 a pre-formed sheet of metal, or by forcing the arc-shaped clips over the ends of a normally flat sheet of metal which is bent from its normal shape to receive the clips. In the latter instance, the clips 41, 42 hold the sheet 40 in the shape of a trough, although the intermediate portion of the sheet is curved less than the end portions. In either case, the clips maintain the member 40 in its trough shape indefinitely and form a protective bearing for the member which prevents 70 wearing of the ends thereof. Preferably, the

member 40 is provided with transverse beads 43, the purpose of which will be described presently. The end clips 41 and 42 are provided with slots 41' and 42', respectively, and the member 40 is mounted in the casing with the V-shaped portion 26 of the mounting element 25 seated in the slot of clip 41, and the notched portion 37 of the bell crank lever seated in the slot in clip 42.

A screw 46 in the front wall of the casing extends through one leg of a generally U-shaped spring member 47 in the casing and through the corresponding leg of a similarly shaped conducting member 48 within the spring member. The members 47 and 48 are held against the front wall of the casing by a plate 49 extending through one side of the casing and through openings in the members 47 and 48, the plate being clamped against the front legs of the members by the screw 46. The rear legs of members 47 and 48 extend transversely across the recess 21 and carry at their outer ends a pin 50 extending therethrough and provided with a head 51 forming a contact, the pin being held by its head and a shoulder 50' against axial movement relative to the members 47 and 48. At its rear end, the pin 50 extends into a central bore in an insulating button 52 seated against the rear legs of members 47 and 48 and engaging the front face of member 40. Another plate 53 extends through the opposite side of the casing into recess 21 and is secured by a screw 54, the two plates 49 and 53 being separated and insulated from each other. At its inner end, the plate 53 carries a contact 55 coating with the contact 51. The plates 49 and 53 are provided at their outer ends with screws 49' and 53', respectively, to which lead wires from an electric device to be controlled may be connected.

In operation, the snap-acting member 40 normally engages the button 52 and holds contact 51 in engagement with the contact 55. When the temperature increases, the member 40 expands against the mounting element 26 and lever 29, so that an endwise compression is imposed on the member. By reason of its trough shape, the member 40 resists the tendency to buckle away from the contacts during the initial compressing action, and the button 52 as well as the normal resistance of member 40 to buckling prevent it from buckling toward the contacts. However, when the endwise compression of the member is sufficient to overcome its resistance to a change in form, the member buckles a' uply away from the button 52 and allows the contact 51 to snap away from contact 55 under the action of the spring 47. The buckling of member 40 is accompanied by a bending thereof transversely at a region intermediate its ends and by a consequent flattening of the intermediate part of the member. When the temperature decreases, the snap-acting member contracts so that the compression thereon is gradually released, and when the compression is reduced to an amount at which the tendency of the snap-acting member to assume its normal trough shape can assert itself, the member snaps abruptly to its initial position in which it holds the contact 51 against contact 55.

The critical temperature at which the snap-acting member moves back to its normal contact closing position is somewhat lower than the critical temperature at which it buckles upon a rise in temperature, this "lagging" being due to the elastic deformation of the member during compression which causes it to elongate slightly when it buckles and relieves the compression. Before

the member can snap to its initial position, it must then cool to a temperature below the critical buckling temperature, until it contracts an amount equal to this elongation.

5 The critical temperature at which the snap-acting element buckles under compression may be varied by operating the handle 35. That is, by turning the handle in one direction, the shaft 34 is screwed inwardly against the horizontal surface 36 of the bell crank lever and urges the lever in a clockwise direction about its pivot 30 (Fig. 1). The notched portion 37 of the lever is thus moved toward the snap-acting member and decreases the spacing between the confining means therefor, whereby the member 40 does not have to expand to as great an extent to acquire the requisite compression for buckling it and will buckle at a lower critical temperature. Conversely, when the handle 35 is turned in the opposite direction, the inner end of shaft 34 is moved outwardly away from the bell crank lever, so that an appreciable expansion of the snap-acting member is required before the bell crank lever is forced against the end of shaft 34. By properly calibrating the instrument, the critical temperature at which the snap-acting element buckles for any adjustment of the handle will be indicated by the position of the handle relative to the scale of graduations (not shown).

10 The device may be "cold checked" by measuring at room temperature the distance through which the notched portion 37 of the bell crank lever must be moved toward the mounting 26, for any given setting of the handle, to buckle the snap-acting member. The coefficients of expansion of member 40 and casing 20 being known, the increase in temperature above room temperature necessary to expand the member against its confining means 26 and 37 an amount equal to the distance measured, may be readily computed.

15 The casing 20, being made of a material having a low coefficient of expansion, does not expand to any appreciable extent when the temperature rises, and, therefore, the effect of the expansion of the casing on the operation of the snap-acting member is negligible. As the temperature rises and expands the member 40 against its confining means, the beads 43 are flexed by the compression and store potential energy which is suddenly released when the member buckles, whereby the snap-action of the member is accentuated. Also, the beads 43 serve to relieve the strain on the snap-acting member incident to sudden compressions thereof. By reason of the end clips 41 and 42, the snap-acting member is centered with respect to its confining means 26, 37 and is held against lateral, edgewise shifting between the confining means. In addition, the end clips prevent wearing of the ends of the member 40, so that the effective length thereof remains constant.

20 The amplitude of the motion transmitted from the snap-acting member to the contact 51 may be varied by the adjustment screw 24 to suit different requirements. When it is desired to decrease the amplitude, the screw 24 is turned so as to move the mounting element 25 forwardly in the passage 21', thereby moving the snap-acting member forwardly and increasing its pressure on the button 52 which is backed by the closed contacts. The snap-acting member is thus bent slightly outwardly by the button 52 in the direction in which the member buckles. Accordingly, when the compression on the snap-acting member is sufficient to buckle it, the intermediate por-

tion thereof moves a shorter distance away from the contact 58 and decreases the rearward movement of the button under the action of spring 47. When it is desired to increase the amplitude, the screw 24 is turned in the opposite direction so as to move the mounting element 26 and snap-acting member 40 rearwardly and decrease the pressure exerted by member 40 against button 52. The intermediate portion of the snap-acting member then moves away from the fixed contact 58 a greater distance when the element buckles and permits a longer movement of button 52 and spring 47.

While the snap-acting member 40 is prevented from buckling rearwardly by reason of its normal engagement with button 52, it is not necessary that the member be backed by a stop to prevent reverse buckling. I have found that by making the member 40 in the form described and subjecting it to compression substantially along its longitudinal median, the compressive force resulting from an increase in temperature tends to buckle it only in the forward direction. Apparently, the reason for this is that the application of compression along the median line results in a loading of the trough member which is eccentric with respect to the true axis of the member, the latter being spaced some distance outwardly from the median line and in front of the concave face of the member. This eccentric loading of the trough member is a significant feature of the new device, because it renders the member capable of buckling under the action of the endwise compression. More particularly, if the trough member were compressed along its true axis instead of an eccentric axis, it would crumple or resist buckling to such an extent that the device would not operate in the manner described. Also, without an eccentric loading of the trough member, it would be difficult to control the direction in which the member buckles. Thus, the eccentric loading not only allows the member to buckle in the proper manner, but also insures that the buckling will take place in the desired direction. Also, while I have illustrated a device in which a pair of closed contacts is opened when the temperature rises to a certain degree, it will be understood that the snap-acting member may be mounted with its concave face adjacent the button 52, whereby the contacts are normally open and are closed by buckling of the member 40.

It will be apparent that the new thermostat may be manufactured at low cost, since the parts are simple and inexpensive and may be readily assembled. The snap-acting member 40, because of its trough shape and inherent spring action, not only buckles abruptly when compressed endwise a sufficient amount, but also snaps back to its normal position when the compression is sufficiently released. Accordingly, I have provided an actuating device which operates abruptly in either direction without the use of bimetallic elements and independently of separate thermo-responsive means, such as a bellows.

The force with which the central portion of the member 40 moves upon buckling depends on the thickness of the sheet metal, the material from which it is made, its normal transverse curvature, and other factors. By suitable selection of the material for the member 40 and proper bending thereof, the operating characteristics of the device may be made to suit the requirements of the particular use to which it is put.

A modified form of the snap-acting member is shown in Fig. 8, the member there shown comprising a sheet of metal 57 bent into the form of a trough. The ends of the sheet are bent forwardly at substantially right angles to the body thereof and form reinforcing end portions 58 and 58' which maintain the sheet in its trough form. A clip 59 is seated on the end portion 58 between the sides thereof and is formed with a part 59' adapted to fit against the mounting element 26 in place of the adjacent end of member 40. The clip is located on the sheet 57 by integral legs 60 extending through slots cut in the side edges of the end portion 58. At the opposite end of sheet 57 is a clip 61 seated on the end portion 58' and formed with a part 62 adapted to fit in the notched portion 37 of lever 29. Integral legs 63 on the clip 61 extend through suitable slots in the side edges of end portion 58' and prevent lateral displacement of the clip.

In the device shown in Figs. 9 to 18, inclusive, the snap-acting element is mounted in a distortible frame adapted to contract endwise and compress the element in response to a rise in temperature. The device comprises a generally diamond-shaped frame 66 formed by a strip of metal, such as Invar, having a low coefficient of expansion, the strip being bent with the ends thereof overlapped at one end of the frame, where they are secured together by means which will be described presently. A cross member 67 of high expansion metal, such as aluminum, extends across the back of the frame and is provided at its ends with forwardly extending legs 68 (Fig. 12). The legs 68 are of greater width than the cross member and are formed to fit against the inner surface of strip 66 at opposite corners of the frame, where the legs are secured by screws 69.

Projecting from the cross member 67 and preferably integral therewith are two oppositely extending arms 70 and 71. A sheet of insulating material 72 is disposed on the front face of the arms 70, 71 and extends from the upper end of arm 71 to the lower end of arm 70. Mounted on arm 70 near the lower end thereof is an upwardly extending contact arm 73, the lower end of which is clamped between the head of a bolt 74 and a spacing washer 75 on the bolt. The contact arm 73 carries on its front face a contact member 76 disposed substantially midway between the ends of cross member 67, and on its rear face a stop 73'. A second contact arm 77 is mounted on arm 71 and is clamped near its upper end between the head of a bolt 78 and a spacing washer 79. The contact arm 77 extends downwardly and carries on one side of its free end a contact member 80 coacting with the contact member 76, and on the opposite side an insulated projection 77'.

The bolts 74 and 78 extend rearwardly through openings in the sheet 72 and through insulating sleeves 74' and 78' fixed in the arms 70 and 71, respectively. Insulating washers 81 and 82 are mounted on the threaded ends of bolts 74 and 78, respectively, and are held in engagement with the back of arms 70 and 71 by washers 81' and 82' backed by nuts 83 and 84, respectively, threaded on the bolts. Preferably, an adjustment screw 85 is mounted in a threaded opening in the cross member 67 with the end of the screw in engagement with the back of insulating sheet 72 opposite the stop 73'. By turning the screw 85, the central portion of insulating sheet 72 is moved toward or away from cross member 67,

whereby the position of the free ends of contact arms 70, 71 may be adjusted.

A wire 86 has one end clamped between the metallic washer 81' and nut 83 and leads to an electrical apparatus (not shown) which is to be controlled. Another wire 86', in circuit with wire 86 through the electrical apparatus, is clamped between the metallic washer 82' and nut 84. It will be observed that the circuit including wires 86 and 86' also includes contact arms 73 10 and 71 and accordingly will be under the control of contacts 76 and 80.

The overlapping portions of the strip 66 are provided with aligned openings in which is threaded one end of a hollow stem 87. The stem 87 is formed with a shoulder 87' which bears against the outer face of strip 66 and is locked on the frame by a nut 88 screwed tightly on the threaded inner end of the stem. The stem 87 extends outwardly from the frame and is internally threaded to receive a screw shaft 89 which carries at its outer end a handle 90 having a pointer 90'. The handle and pointer cooperate with a temperature scale (not shown) arranged on a panel 91 which is secured against rotation in any suitable manner. A pin 92 is slidable in the inner end of stem 87 and rests against the corresponding end of shaft 89, the free end of the pin being formed with a transverse slot 93.

The end of frame 66 opposite the pin 92 is flattened, as shown, and has a block 94 secured to the inner face thereof by rivets 95. A pin 96 is threaded into the block 94 and strip 66 and has an enlarged head provided with a transverse slot 97.

Seated at its opposite ends in the transverse slots 93 and 97 is a flexible sheet of high expansion metal 99, preferably unimetallic. As shown particularly in Figs. 13, 14 and 15, the sheet 99 is elongated and is bent transversely into a trough shape, the sheet being preferably substantially straight in the direction of its length. The back of the sheet, as shown in Fig. 11, normally engages the projection 71' on contact arm 71 and thereby maintains the contacts 76 and 80 closed against the spring action of arm 71.

When the device is subjected to heat, the cross member 67 expands against the opposite sides of the relatively in-expansive frame 66, thereby causing the pins 92 and 96 to move together and compress the flexible sheet 99 endwise. At the same time, the sheet 99 expands against pins 92, 96 under the action of the heat, and this expansion adds to the endwise compression of the sheet. The sheet, due to its configuration, resists the force tending to buckle it away from the contacts during the initial compressing action, and is prevented from buckling toward the contacts by engagement with the projection 71'. The contacts are thus held by the sheet in a closed position against cross arm 71. However, when the endwise compression of the sheet reaches a critical amount, its resistance to a change in shape is overcome so that the sheet buckles away from the contacts (Figs. 16, 17 and 18). The buckling of the sheet is accompanied by a bending thereof transversely at a region substantially intermediate its ends and by a consequent flattening of the intermediate part of the sheet. The sheet thus releases the projection 71' and allows the contacts 76, 80 to snap to their normally open positions.

When the temperature decreases, the cross arm

67 contracts and draws the sides of frame 66 inwardly, and as a result the ends of the frame are moved outwardly toward their initial positions, thereby gradually releasing the compression on the flexible sheet 99. Simultaneously, the sheet 99 contracts and further decreases the compression thereof. When the compression is reduced to a critical amount at which the tendency of the sheet to assume its normal position can assert itself, the sheet snaps abruptly to its initial position in which it holds the contacts 76, 80 together against the insulating sheet 12.

By manipulating the handle 90, the inner end of shaft 89 may be moved toward or away from the sheet 99 so as to vary the amount of expansion of the sheet necessary to effect its buckling, and as the handle is turned, the pointer 90' indicates on the panel 91 the critical temperature at which the sheet will buckle. Also, by adjusting the set screw 85, the central portion of insulating sheet 72 and stop 71' may be forced outwardly against the sheet 99, so that the latter is bent slightly toward its buckled position and exerts a greater pressure on the contacts. With this adjustment, it will be apparent that the intermediate portion of the sheet 99 moves through a shorter distance during operation of the thermostat, whereby the amplitude of the movement of arm 71 is decreased. While the sheet 99, as shown, is made of a thermo-expansive metal, such as a nickel-steel alloy, it may be made of a material having a negligible coefficient of expansion so that the compression thereof is effected substantially entirely by the frame.

35 I claim:

1. An actuating device comprising a sheet of flexible material, curved members secured to the ends of the sheet for holding it in a generally trough shape, and means for subjecting the sheet to endwise compression, said curved members having recesses therein for receiving said means to locate the sheet relative to said means, said sheet being operable to buckle abruptly when compressed a predetermined amount and to return abruptly to its original position upon release of the compression.

2. An actuating device comprising a pair of bowed clips having recesses therein, a sheet of flexible material having its ends held by the clips, said clips and sheet forming a generally trough-shaped element, and means at the ends of said element engaged in said recesses for subjecting the element to endwise compression, said element being operable to buckle abruptly when compressed a predetermined amount and to return abruptly to its original position upon release of the compression.

3. An actuating device comprising a snap element, control means coacting with the snap element intermediate its ends, curved members secured to the ends of the snap element for holding it in a trough shape and having slots therein, movable seats for the snap element at the opposite ends thereof for compressing the element and buckling it, the seats being engaged in said slots to locate the sheet relative to the seats, adjustment means for moving one of the seats toward the other seat to vary the compression in the snap element, and adjustment means for moving the second seat laterally relative to the first seat and in the direction of buckling to vary the throw of the snap element relative to the control means.

LYNDON W. BURCH.
